TALLY DEVICE

Margaret Bristol, New York, N. Y.

Application March 6, 1948, Serial No. 13,400

5 Claims. (Cl. 235—123)

1

This invention relates to a knit kit.

More specifically, the invention proposes the construction of a knit kit which is a utility kit having recording apparatus for keeping an accurate count of the rows knitted in following a pattern or design and which also contains all the necessary articles for hand knitting as well as a space in which the article being knitted may be stored when not being worked upon and for convenient carrying about.

A further object of this invention proposes the construction of a recording apparatus for the interior of the knit kit which in addition to keeping an accurate count of the rows knitted, also clearly indicates the type of stitch to be made in a particular row.

Still further the present invention proposes the construction of a knit kit in the form of a case having a hollow bottom and a hollow hinged cover, the bottom being constructed to contain the recording apparatus, space for a ball of yarn being worked and cells for the knitting apparatus and the article being knitted while the hinged cover has a space for pattern books together with a suitable means for retaining the books in position, and space for additional knitting apparatus and additional yarn.

Another object is to provide a knit kit as aforesaid in which the counter compartment is covered by a transparent plastic plate having individual transparent plastic leaves extending longitudinally over each row of counters, each leaf being held at its free end by a latch which is designed to hold the leaf tightly against the top of the counters to retain the counters against accidental movement, the purpose of the plastic plate being to prevent accidental movement of the wrong counter, as by brushing with a coat sleeve inadvertently, while still leaving the counters visible.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a rectangular knit kit constructed in accordance with this invention.

Fig. 2 is a front elevation of the kit of Fig. 1.

Fig. 3 is a plan view of the kit with the cover in open position.

Fig. 4 is a section on the line 4—4 of Fig. 3.

2

Fig. 5 is an enlarged detail view of a portion of Fig. 3.

Fig. 6 is a perspective view of one of the stitch indicating members.

Fig. 7 is a perspective view of a stitch indicating member constructed in accordance with a modification of this invention.

Fig. 8 is a view similar to Fig. 1 of a circular knit kit.

- 10 The knit kit constructed in accordance with the present invention includes a case 10 formed of a bottom 11 and a hollow cover 12 hinged thereto. A rectangular case is shown in Figs. 1-3. It is contemplated that a suitable size for 15 such a case would be fifteen inches long by thirteen inches wide by four inches high. The cover is about half as deep as the bottom 11. The top wall 13 of the cover and the bottom wall 14 of the bottom 11 may be made of Masonite. 20 The four side walls of the cover 12 and the four side walls of the bottom 11 may be made of wood with mortis and tenon joints at the corners. The case may be covered, exteriorly, by attractive leatherette or fabricoid of any desired color, and may be lined interiorly with a gay chintz or matching rayon.

Two locks 15 secure the cover 12 to the bottom 11 when the case is closed. The bottom 11 is provided with a handle 16 at its side remote 30 from its hinges. The bottom 11 is partitioned by a longitudinal wall 17 into a large cell 18 and a smaller cell 19. The smaller cell 19 is partitioned by a transverse wall 20 into a small square compartment 21 and into a long compartment 22. Wall 17 is mortised into the side walls of the bottom 11 and wall 20 is mortised into the wall 17 and into the front wall of the bottom 11.

Compartment 21 has a chintz covered hinged 40 top 23 in which is a central hole 24. Compartment 21 is for containing a ball or balls of yarn. The yarn will feed through the hole 24 as it is being used. The compartment 22 is for containing various knitting implements. It is shown 45 containing bodkins 26, a darning needle 27, a ruler 28, scissors 29, a crochet hook 30 and stitch holders 31. These are held in place by loops of fabricoid or elastic 32.

Compartment 18 contains twelve transverse 50 equally spaced rods 33 secured at their ends in the rear wall of bottom 11 and in the wall 17. The rods are spaced a short distance from the wall 14. A plurality of circular discs or counters 34 are mounted on each rod. The drawing 55 illustrates six discs or counters 34 on each rod,

but it is pointed out that any desired number of discs or counters, as many as twelve, could be mounted on each rod. The discs are in rows of different colors or shades of colors and are preferably made of plastic. They have central holes 35 by means of which they are mounted on the rods. The discs or counters 34 have a friction fit on the rods 33 so that when the counters are moved on the rods, they remain in the position to which they were moved.

The cover 12, is, as aforesaid, hollow. Two parallel walls 36 partition the cover transversely into a narrow right cell 37, a narrow left cell 38 and a large middle compartment 39, the walls 36 being parallel to the side walls of the cover. Walls 36 are mortised into the front and rear walls of the cover. The compartment 39 contains several books. The walls 36 each has two spaced recesses 40 in each of which is pivotally connected a tab 41. The tabs have frictional contact with the walls 36 and will stay in any position to which they are swung. Their active position for retaining the books in the compartment 39 is indicated in Fig. 3 in dot-dash lines.

Cells 37 and 38 are provided with other holders 32. The holder 32 of cell 37 retains two sets of sock knitting needles 42 while the holder 32 of cell 38 retains four sets of knitting needles 43 for general use.

The counter compartment is completely covered by a plastic transparent plate 44. This plate is mortised into the rear wall of the compartment, the joint at the rear wall being clearly shown in Fig. 4. The plate is cut by transverse slits to provide twelve fingers 45, one over each row of counters. These fingers can hinge about their integral connection with the part of the plate mortised into the rear wall as aforesaid. The free end of each finger is secured to the wall 17 by a small spring latch 46. When the finger is latched in place, it engages the tops of the counters sufficiently to prevent, by augmenting the frictional contact of the counters on their rods, any inadvertent movement such as might occur when a coat sleeve brushes one counter when another is being moved. The knitter lifts only the finger over the counter which she wishes to move, and the other counters are protected while still being visible.

Stitch indicating members 50 are provided for use in connection with the rows of counters for indicating the type of stitch to be made in each row. The stitch indicating members 50 include top portions 51 preferably made of plastic material, wood or other similar material and clip portions 52 integrally connected with the top portions 51 and preferably constructed of spring steel or other flexible material. The top portions 51 are provided with identifying letters, such as the letter "K" shown in Fig. 6. The kit is provided with a plurality of these stitch indicating members 50 and each carries a different letter. For example, one group of members will have the letter "K" (as shown) to indicate a "knit" stitch, another group of members 50 will have the letter "P" to indicate a "purl" stitch, and so on, there being a group of members 50 having the appropriate letter or letters to indicate each type of knitting stitch.

The clip portions 52 of the stitch indicating members 50 are adapted to be extended through openings 53 (see Fig. 5) formed in the transparent plastic plate 44 to be engaged over retaining blocks 54 fixedly mounted on the rods 33 beneath the openings 53 and behind the end-most disc

or counter 34 on the particular rod. The construction is such that with the clip portions 52 in position on the retaining blocks 54, the top portions 51 extend above the top face of the transparent plate 44 so that the letter thereon is plainly visible without the necessity of lifting any of the finger portions of the plate 44. The construction also permits the stitch indicating members to be conveniently interchanged when desired.

In Fig. 7 of the drawing, a modified type of stitch indicating member 60 is illustrated which differs from the previous member 50 in that the member 60 is formed entirely of plastic material or other similar flexible material. The member 60 has a top portion 61 and an integral clip portion 62 and the top portion is formed with the stitch indicating letter 63. The stitch indicating letter 53 of the member 50 or the letter 63 of the member 60 may be formed by printing, painting, embossing or in any other similar manner.

A round knit kit is shown in Fig. 8. It differs from the knit kit of Figs. 1-3 essentially only in its shape. The case bottom 11 has two walls 11a and two walls 20a. Parts which correspond to like parts of the embodiment of the invention shown in Figs. 1-3 are indicated by like references with the suffix *a* added. No further description thereof is deemed necessary.

Each of the rows of counters 34 is, as aforesaid, in both embodiments of the invention, of a different color, and these rows of counters are used for counting purposes to keep tally as the knitting proceeds. The person doing the knitting is also able to keep track of different stitches in each row of knitting in a desired pattern by arranging the stitch indicating members according to the pattern desired. The counters 34 enable the knitter to keep track of the rows and/or stitches already knitted without the use of a pencil and paper, the use of which requires laying down and interrupting the knitting, which interruption is liable to lead to mistake. These counters are placed low enough in the kit, as shown, so that the knitting may be placed on top of the counters when it is desired to store the knitting away.

The inner surfaces of the case, including cells, compartments, walls and covers, are all lined with the same design of chintz or other suitable cloth. The advantages of the knit kit are its convenience, its neatness and attractiveness, the accuracy which it provides, the avoidance of making notes with paper and pencil while knitting, and the inclusion of all articles needed in one kit.

The case is preferably made with plywood sides and partitions, but any other suitable materials may be used here if desired. The cover swings to a fully open position and may be supported in a desired open position so that its entire inner surface is accessible to the knitter, whereby the knitter can use the counters, and follow the instruction book at the same time. The knit kits illustrated in the drawings are by way of illustration only and the cases, counters and stitch indicating members may be varied in size and shape as desired.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new, and desire to secure by United States Letters Patent is:

1. In a knit kit, a body having an open topped chamber, a plurality of rods mounted within said chamber between opposed walls thereof and extended parallel to each other, a plurality of counters slidably mounted on each of said rods, each of said counters being formed with a central bore through which the respective rod extends and being of a diameter so that the material of each counter defining said bore frictionally grips the respective rods to frictionally retain said counters in desired shifted positions on said rods, and auxiliary means for assisting said frictional mounting of said counters on said rods in retaining said counters in a desired shifted position on said rods, said auxiliary means comprising a transparent flexible plate positioned within said chamber and mounted along one edge on one of said opposed walls and having its opposite edge spaced from the other of said opposed walls, said plate being mounted within said chamber at a level so that its bottom face frictionally bears against the top face of said counters, said plate being formed with a plurality of slits extended from its said opposite edge toward but not through its said one edge, said slits being extended parallel to said rods with one slit between each adjacent pair of rods forming a plurality of fingers each bearing against the top portions of the counters on one of said rods and having a free end adjacent the said other wall by which the fingers can be individually flexed upward freeing said counters to be slid along the length of said rods.

2. In a knit kit, a body having an open topped chamber, a plurality of rods mounted within said chamber between opposed walls thereof and extended parallel to each other, a plurality of counters slidably mounted on each of said rods, each of said counters being formed with a central bore through which the respective rod extends and being of a diameter so that the material of each counter defining said bore frictionally grips the respective rods to frictionally retain said counters in desired shifted positions on said rods, and auxiliary means for assisting said frictional mounting of said counters on said rods in retaining said counters in a desired shifted position on said rods, said auxiliary means comprising a transparent flexible plate positioned within said chamber and mounted along one edge on one of said opposed walls and having its opposite edge spaced from the other of said opposed walls, said plate being mounted within said chamber at a level so that its bottom face frictionally bears against the top face of said counters, said plate being formed with a plurality of slits extended from its said opposite edge toward but not through its said one edge, said slits being extended parallel to said rods with one slit between each adjacent pair of rods forming a plurality of fingers each bearing against the top portions of the counters on one of said rods and having a free end adjacent the said other wall by which the fingers can be individually flexed upward freeing said counters to be slid along the length of said rods, and latch means for holding down the free ends of each of said fingers.

3. In a knit kit, a body having an open topped chamber, a plurality of rods mounted within said chamber between opposed walls thereof and extended parallel to each other, a plurality of counters slidably mounted on each of said rods, each of said counters being formed with a central bore

through which the respective rod extends and being of a diameter so that the material of each counter defining said bore frictionally grips the respective rods to frictionally retain said counters in desired shifted positions on said rods, and auxiliary means for assisting said frictional mounting of said counters on said rods in retaining said counters in a desired shifted position on said rods, said auxiliary means comprising a transparent flexible plate positioned within said chamber and mounted along one edge on one of said opposed walls and having its opposite edge spaced from the other of said opposed walls, said plate being mounted within said chamber at a level so that its bottom face frictionally bears against the top face of said counters, said plate being formed with a plurality of slits extended from its said opposite edge toward but not through its said one edge, said slits being extended parallel to said rods with one slit between each adjacent pair of rods forming a plurality of fingers each bearing against the top portions of the counters on one of said rods and having a free end adjacent the said other wall by which the fingers can be individually flexed upward freeing said counters to be slid along the length of said rods, spring latches mounted on the said other wall, one for each of said fingers, and engaged by the free ends of said fingers for holding down the free ends of said fingers.

4. In a knit kit, a body having an open topped chamber, a plurality of rods mounted within said chamber between opposed walls thereof and extended parallel to each other, a plurality of counters slidably mounted on each of said rods, each of said counters being formed with a central bore through which the respective rod extends and being of a diameter so that the material of each counter defining said bore frictionally grips the respective rods to frictionally retain said counters in desired shifted positions on said rods, and auxiliary means for assisting said frictional mounting of said counters on said rods in retaining said counters in a desired shifted position on said rods, said auxiliary means comprising a transparent flexible plate positioned within said chamber and mounted along one edge on one of said opposed walls and having its opposite edge spaced from the other of said opposed walls, said plate being mounted within said chamber at a level so that its bottom face frictionally bears against the top face of said counters, said plate being formed with a plurality of slits extended from its said opposite edge toward but not through its said one edge, said slits being extended parallel to said rods with one slit between each adjacent pair of rods forming a plurality of fingers each bearing against the top portions of the counters on one of said rods and having a free end adjacent the said other wall by which the fingers can be individually flexed upward freeing said counters to be slid along the length of said rods, a retaining block mounted on each of said rods on the end thereof adjacent the mounted edge of said plate, said plate being formed with an opening aligned with each of said retaining blocks, and stitch indicating members extendable through said openings for engagement on said retaining blocks.

5. In a knit kit, a body having an open topped chamber, a plurality of rods mounted within said chamber between opposed walls thereof and extended parallel to each other, a plurality of counters slidably mounted on each of said rods, each of said counters being formed with a central bore

through which the respective rod extends and being of a diameter so that the material of each counter defining said bore frictionally grips the respective rods to frictionally retain said counters in desired shifted positions on said rods, and auxiliary means for assisting said frictional mounting of said counters on said rods in retaining said counters in a desired shifted position on said rods, said auxiliary means comprising a transparent flexible plate positioned within said chamber and mounted along one edge on one of said opposed walls and having its opposite edge spaced from the other of said opposed walls, said plate being mounted within said chamber at a level so that its bottom face frictionally bears against the top face of said counters, said plate being formed with a plurality of slits extended from its said opposite edge toward but not through its said one edge, said slits being extended parallel to said rods with one slit between each adjacent pair of rods forming a plurality of fingers each bearing against the top portions of the counters on one of said rods and having a free end adjacent the said other wall by which the fingers can be individually flexed upward freeing said counters to be slid along the length of said rods, a retaining block mounted on each of said rods on the end thereof adjacent the mounted edge of said plate, said plate being formed with

5. an opening aligned with each of said retaining blocks, and stitch indicating members extendable through said openings for engagement on said retaining blocks, each of said stitch indicating members having a portion projected above the top face of said plate when mounted on said retaining blocks, and indicia on the portions of said members which project above the top face of said plate for indicating stitch types.
